UNITED STATES PATENT OFFICE.

ORVILLE W. SHRADER, OF BOAZ, ALABAMA.

BEE-SMOKER.

1,386,283.

Specification of Letters Patent.

Patented Aug. 2, 1921.

Application filed June 8, 1920. Serial No. 387,327.

To all whom it may concern:

Be it known that I, ORVILLE W. SHRADER, a citizen of the United States, residing at Boaz, in the county of Marshall and State 5 of Alabama, have invented new and useful Improvements in Bee-Smokers, of which the following is a specification.

The object of the invention is to provide an efficient and simple construction of apparatus for smoking bees under such conditions as to provide for varying the temperature of the smoke to suit the conditions under which the operation is being conducted, the means for securing such modification or variation being within the convenient control of the operator, and with this object in view the invention consists in a construction and combination of parts, of which a preferred embodiment is shown 20 in the accompanying drawings, wherein:—

Figure 1, is a side view partly in section of an apparatus embodying the invention.

Fig. 2, is a transverse sectional view of the same on the plane indicated by the line 25 2—2 of Fig. 1.

The device consists essentially of the furnace or fire box 10, which as illustrated may be of cylindrical form having a grate 11 and an outlet or discharge nozzle 12 through 30 which the smoke may be ejected, and a draft apparatus consisting of a collapsible bellows 13 having communication with said furnace or fire box, through the conductor tubes 14 and 15 respectively located near the top and 35 beneath the plane of the grate 11 of the furnace or fire box, said conductors being provided respectively with cut-off slides or valves 16 and 17 either of which may be closed to enable the operator to discharge 40 a blast of air either through the body of the fire on the grate or through the top of

the fire box above the plane of the grate according to whether a hot or a cold blast or discharge of smoke is desired. Obviously in the use of the lower conductor which may 45 be effected by the closing of the slide valve 16 and opening valve 17 the fuel supported by the grate is stimulated by a draft blast through the same, and in this way a hot and dense discharge of smoke through the outlet 12 may be secured, whereas when a less dense distribution of smoke at a lower temperature is sufficient for the purpose in view, the positions of the slide valves may be reversed to cause a discharge of air from the 50 bellows through the upper conductor 14 and thence through the outlet 12.

The invention having been described, what is claimed as new and useful is:—

1. A bee smoker having a fire box or furnace provided with a terminally disposed spout or outlet, a fuel supporting grate, a collapsible bellows, conductors connecting the interior of the bellows with the fire box or furnace respectively above and below the 60 plane of the grate, the upper conductor being arranged adjacent to the plane of said discharge spout or outlet and independent slide valves for controlling the said conductors.

2. A bee smoker having a fire box or furnace provided with a terminal discharge pipe or outlet and an intermediate fuel supporting grate, and means for introducing an air blast into the furnace and provided 75 with selective control devices whereby the blast may be introduced just below the plane of the discharge pipe or below the plane of the supporting grate.

In testimony whereof I affix my signature.

ORVILLE W. SHRADER.
